PITCHER

Frank J. Vazzano, Nichols, Conn.

Application April 4, 1950, Serial No. 153,779

5 Claims. (Cl. 62—146)

1

This invention relates to new and useful improvements in receptacles and has particular relation to a pitcher for use in the making of ice water, iced tea and the like and for containing the liquid until the same is poured and used.

An object of the invention is to provide a pitcher adapted to have liquid poured therefrom and also adapted to have ice formed therein and into which receptacle water or other liquid, as tea, may be poured to be cooled by the ice and from which the iced liquid may be poured in the usual manner.

Another object is to provide a pitcher or pouring receptacle of the character indicated which is substantially completely closed while in a refrigerator or while in use and which is made up of but a few parts readily and permanently assembled for use.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a side elevational view showing the complete pitcher of the invention;

Fig. 2 is a vertical sectional view through the same, the view being taken as along the line 2—2 of Fig. 1;

Fig. 3 is a horizontal sectional view through the pitcher, the view being taken as along the plane of the line 3—3 of Fig. 1; and

Fig. 4 is a view similar to Fig. 3 but taken along the plane of the line 4—4 of Fig. 1.

Referring in detail to the drawing, my improved pitcher comprises a rectangular body generally designated 10 including a bottom wall 11 and side walls 12, 13, 14 and 15. Wall 15 may also be described as a front wall and through the upper edge portion thereof is a pouring opening 16 and fast with the wall, in position to receive liquid moving out through said pouring opening, is a pouring spout 17.

Integral with the bottom wall 11 are a pair of dividing plates 18 and 19. These plates at their ends are also integral with the walls 13 and 15. These plates 18 and 19 are relatively shallow and thin and serve to divide the lower portion of the body 10 into three equal or substantially equal compartments 20, 21 and 22.

2

Integral with the end portions of the upper edge of the dividing plate 18 and also integral with the body walls 13 and 15 are ribs or extensions 23 and 24. Similar and equal size ribs 25 and 26 are integral with the end portions of the upper edges of the plate 19 and with adjacent portions of the walls 13 and 15. All of these ribs are of the same height.

Within the body 10 and resting on the upper ends of plate extensions or ribs 23, 24, 25 and 26 is a bifurcated or U-shaped tray or receptacle open at its upper side generally designated 27. This tray 27 includes a bottom wall comprising arm portions 28 and 29 and a connecting portion 30 and upstanding from said bottom wall is a side wall comprising outer portions 31, 32 and 33 and a spaced pair of such portions 34 and 35. In addition, such upstanding wall includes a U-shaped portion comprising side or arm portions 36 and 37 and a connecting portion 38.

The tray is of such size and shape as to have a relatively snug fit into the receptacle so that under surfaces of the bottom wall of the tray will rest on the upper ends of the ribs or extensions 23, 24, 25 and 26 while the outer side wall portions 31—35 of the tray engage inner surface portions of said walls of the body. Thus, outer side wall portion 31 of the tray is against side wall 12 of the body while side wall portion 32 of the tray is against the inner surface of wall 13 of the body, side wall portion 33 of the tray is against the inner surface of side wall 14 of the body and spaced side wall portions 34 and 35 of the tray are against spaced portions of the inner surface of the body side wall 15.

With this construction, it will be understood that the tray 27 is supported within the body, in a position spaced above the bottom of the body and, in fact, spaced above the upper edges of the dividing plates 18 and 19 and is held against any downwardly or lateral movement in the body. The fit of the tray should be such snugness that it will stay in place and not move upwardly on tilting of the body and, if desired, the tray may be adhesively secured, as by bonding, with portions of the body in the position shown and described.

The upper edge of the front wall 15 of the body extends higher than the rear wall 13 thereof and the forward portions of the side walls 12 and 14 are higher than the rear portions of such walls. This is as fully illustrated in Fig. 1. The upper side of the hollow body or receptacle 10 is permanently closed by a cover structure generally designated 39.

Such cover structure includes upper plate-like portion 40, an intermediately downwardly inclined plate-like portion 41 and a rear plate-like portion 42 in a plane below but parallel with that of the cover portion 40. Thus, this upper cover portion is designed to lie against the upper edges of the various side walls of the body.

Depending from this upper cover portion is a rather shallow flange 43 telescopically received at the inner sides of the mentioned side walls of the body and these flanges are adhered or bonded to contacted portions of the body walls while the upper cover portion 40, 41 and 42 is similarly connected with the upper edges of the side walls of the body. It is intended that the entire pitcher be made of a suitable plastic and the cover may be secured in place by adhesive or through the use of heat to soften portions of the cover and body while in engagement to have them fuse or bond together.

Extending upwardly from cover portion 42 towards the rear end of the latter is a hollow post-like part 43 and extending between said part and integral therewith and with the cover portion 41 is a strap-like portion 44 having a hand or finger receiving opening 45 therethrough. Thus, this portion 44 forms a handle by means of which the pitcher may be carried, manipulated for pouring, etc.

Hollow post-like portion 43 provides a filling opening. This portion is open vertically through both its ends whereby liquid may be poured into the pitcher through said portion. When the present pitcher is not being filled, the opening through portion 43 is closed as by a stopper 46.

When the present pitcher is to be used, water is poured through post-like portion 43 and falls into the connecting portion of the tray 27. In this connection it will be understood that the hollow post 43 is in the longitudinal center line of the cover and thus midway between the side edges of the cover.

As the liquid continues to be poured into the pitcher, the tray 27 becomes filled and then the overflow from the tray moves over the wall portions 36, 37 and 38 into the bottom central compartment 21. When said compartment becomes filled, water overflows the upper edges of the dividing plates 18 and 19 until compartments 20 and 22 are filled. At this point, the pouring of liquid into the receptacle is stopped. Now the stopper 46 is positioned and the receptacle placed in the freezing compartment of a refrigerator or the like whereby to freeze the liquid which has been poured into the receptacle.

The ice so formed remains in the receptacle and the receptacle may remain in the refrigerator until iced drinks are to be served. At such time, water, tea, etc., is poured in through the passage in the post-like portion 43 filling the lower portion of the receptacle and filling the same up to approximately the bottom end of the outlet opening 16 in the upper edge portion of the front wall of the body.

With the described construction, it will be seen that the upper surfaces of the blocks of ice in the various compartments 20, 21 and 22 and the upper surfaces of ice in the tray are all exposed to this liquid which has been introduced whereby the latter will be rapidly cooled. As the pitcher is tilted to pour, even though the ice may have become loosened from the tray or from the compartments and tend to float, it cannot

move through the pouring opening as the ice is formed in large portions.

In fact, if the ice does float loose, more rapid cooling action is obtained since then all surfaces of the ice are exposed to the liquid. It is additionally pointed out that the tray being constructed in the shape shown, in any pouring action, liquid in the lower portion of the receptacle may pass outwardly along the inner surface of the wall 15 through the opening between the tray portions 36 and 37 to the pouring opening 16 and thence the pouring spout 17. Thus, the tray does not interfere with pouring from the receptacle.

It is contemplated that the present pitcher will be molded of a suitable plastic and such plastic may be transparent or colored to suit. The pitcher is a special purpose pitcher and when not in use may be left in the refrigerator and is given the rectangular shape shown to have it better fit within a refrigerator. Essentially, if molded, it comprises but the body, tray and cover and the stopper 46. While it is preferred to make it of plastic, because of the lightness and other attractive features, it will be understood that I am not limited to a pitcher manufactured of such materials.

The word plastic when used herein to designate a material is employed for the purpose of identifying the various materials commercially identified as plastic and the word is not used in relation to chemical or mechanical characteristics of the material.

Having thus set forth the nature of my invention, what I claim is:

1. In a pitcher, a hollow body including bottom and side walls, said body having a pouring opening through the upper portion of a side wall, a pouring spout to receive liquid moving outwardly through said pouring opening, plates on said bottom wall and extending vertically therefrom and dividing the lower portion of said body into compartments, ribs on said side walls and having their upper ends above the upper edges of said plates, a tray of a size to fit into said body, said tray being U-shaped and having its connecting portion against a wall of the body and its open portion between the free ends of its arms against the body wall having the pouring opening therethrough, a closure spanning the upper end of said body and permanently sealed in place closing the upper end of said body, a lifting handle rigid with said closure, said closure having a filling opening therethrough in such position that liquid entering said receptacle through said filling opening enters the connecting portion of said U-shaped tray, and said U-shape of tray providing means whereby when the tray is filled with liquid the overflow moves between the arm portions of the tray into the compartments in the lower portion of the body.

2. In a pitcher, a hollow body including a generally rectangular bottom wall and upstanding side and end walls integral with the edge portions of said bottom wall, one of said end walls having a pouring opening through its upper edge portion, a pouring spout on said wall to receive liquid moving outwardly through said pouring opening, dividing plates integral at their lower edges with said bottom wall and integral at their ends with said end walls and dividing the lower portion of said body into compartments, ribs on said end walls and having their upper ends above the upper edges of said plates, a tray in said body and resting on the upper ends of said ribs.

said tray having outer walls contacting with the inner surfaces of said end and side walls of the body, said tray having a slot opening through its bottom and front wall, a vertical wall about the edges of said slot whereby said tray is open at its upper side and comprises a bifurcated receptacle, a closure spanning the upper end of said body and permanently sealed in place closing such body end, said closure having a filling opening therethrough in vertical alignment with said tray whereby liquid entering the receptacle through said filling opening fills said tray and then spills over said vertical wall and through the slot in the tray to fill said lower compartments.

3. In a pitcher, a hollow body including bottom and side walls, a pouring opening through one of said side walls, a pouring spout to receive liquid passing out through said pouring opening, means dividing the lower portion of said body into a series of compartments, a tray supported in said body above said means, a filling opening in said body and through which liquid may be poured into said tray, and means whereby overflow from said tray passes into said compartments.

4. In a pitcher, a hollow body including bottom and side walls, a pouring opening through one

of said side walls, a pouring spout to receive liquid passing out through said pouring opening, means dividing the lower portion of said body into a series of compartments, a tray supported in said body above said means, a filling opening in said body and through which liquid may be poured into said tray, means whereby overflow from said tray passes into said compartments, a cover permanently secured to the upper portions of said side walls and closing the upper side of said body, and a handle rigid with said cover.

5. The pitcher as in claim 4 wherein each of said body, tray and cover comprises an integral piece of a lightweight plastic material.
